TRANSFERRER ARM FOR WEFT
REPLENISHING LOOMSGabriel C. Beatrice, Shrewsbury, Mass., assignor
to Crompton & Knowles Loom Works, Worcester,
Mass., a corporation of Massachusetts

Application May 19, 1948, Serial No. 27,941

6 Claims. (Cl. 139—244)

1

This invention relates to improvements in trans-
ferrer arms for weft replenishing looms and it is
the general object of the invention to provide a
transferrer arm which will insure correct move-
ment of a bobbin into the shuttle being replen-
ished.

It is undesirable to have knots in certain kinds
of weft and if the thread breaks during the wind-
ing operation the bobbin is removed from the
winder and placed in the loom reserve bobbin
magazine even though only partly filled. When
such a bobbin is transferred there is likelihood
that its tip end will swing upwardly with respect
to the butt end and interfere with the proper
movement of the bobbin into the shuttle. To
correct this condition it is an important object
of the present invention to provide a transferrer
arm having an auxiliary foot or the like to en-
gage the partly wound bobbin and prevent any
substantial amount of upward movement of its
tip.

In a type of loom which has gone into wide use
the transferrer arm has the usual butt engaging
foot and also a second foot spaced several inches
from the first foot for engagement with the
wound mass of weft. With such a transferrer
arm it has been found that the second foot occa-
sionally acts as a pivot around which the bobbin
swings during transfer in a direction to raise the
tip and it is a further object of the invention to
provide an auxiliary or third foot beyond the sec-
ond foot to prevent the aforesaid upward pivoted
movement of the bobbin tip.

A reserve bobbin magazine can ordinarily be
adapted for bobbins of different lengths if appro-
priate changes are made in the bobbin tip sup-
porting plate and delivery cradles. The trans-
ferrer arm, however, will ordinarily be the same
for all bobbin lengths. It is an additional pur-
pose of the invention to provide an auxiliary bob-
bin engaging foot which can be added to a trans-
ferrer arm when the magazine is adapted for long
bobbins.

With these and other objects in view which will
appear as the description proceeds, my invention
resides in the combination and arrangement of
parts hereinafter described and set forth.

In the accompanying drawings, wherein a con-
venient embodiment of my invention is set forth,

Fig. 1 is a side elevation partly in section of a
weft replenishing loom having the improved form
of transferrer arm applied thereto.

Fig. 2 is an enlarged front elevation partly in
section of the transferrer arm looking in the di-
rection of arrow 2, Fig. 1.

2

Fig. 3 is an enlarged plan view looking in the
direction of arrow 3, Fig. 2.

Fig. 4 is a vertical section on line 4—4 of Fig. 3,
and

Figs. 5 and 6 are vertical sections on lines 5—5
and 6—6, respectively, of Fig. 4.

Referring particularly to Fig. 1, the loom frame
10 supports a reserve bobbin magazine M which in
the present instance carries front and back stacks
11 and 12, respectively, of reserve bobbins which
move by gravity toward transfer position. The
lay 13 is provided with a shuttle box 14 to receive
a shuttle S provided with a bobbin 15. A bunter
16 on the lay engages a latch 17 on a transferring
beat of the loom to cause clockwise angular
movement of a transferrer arm 18 as viewed in
Fig. 1 for the purpose of inserting a reserve bob-
bin B into the shuttle S.

As shown in Fig. 2 the transferrer arm has a
foot 20 for the butt 21 of bobbin B and has also
a second foot 22 spaced several inches from the
first foot in the direction of the length of the
bobbin toward the tip of the latter. The trans-
ferrer arm has top and bottom webs 23 and 24,
respectively, integral with the feet 20 and 22 to
cause both of the feet to descend in unison during
a bobbin transferring operation.

The matter thus far described is of common
construction and of itself forms no part of the
present invention except as noted hereinafter.

In carrying the present invention into effect I
provide means by which the tip or right end T of
bobbin B as viewed in Fig. 2 can be prevented
from moving upwardly sufficiently to interfere
with a proper transferring operation. A carrier
or plate 30 having a vertical web or body 31 is
formed integrally with right, left and bottom
flanges or walls 32, 33 and 34, respectively, see Fig.
4. Screws 35 passing through vertical slots 36 in
flange 33 secure the carrier 30 in adjusted vertical
position to the foot 22 of the transferrer arm.
The carrier can be made as a sheet metal stamping
and can be applied to or removed from the
transferrer arm by reason of the screws 35.

An auxiliary or third foot 40, which may be
made of compressible but resilient material such
as felt, is held against the outer surface of flange
32 by means of screws 41 which pass through a
holding or clamping plate 42 and foot 40 and are
tapped into flange 32, see Fig. 4. The felt pad or
foot 40 may have parallel sides one of which en-
gages the plate 42 and the other of which engages
the flange 32, and its bottom may be inclined
downwardly and toward bobbin tip T, as at 45,
and concave to fit the bobbin, see Fig. 6.

When a full bobbin is being transferred as indicated in Fig. 2 the two feet 20 and 22 and also the auxiliary foot 40 engage the bobbin. The foot 40 effectively prevents upward movement of the tip end of the bobbin during the transferring operation, and its vertical adjustment on foot 22 permits it to be used with different diameters of weft on bobbin B. As shown in Fig. 2 the foot 22 is not very far from the center of gravity of a full bobbin and if the first engagement or blow of the foot 20 against the bobbin butt 21 should cause the latter to move downwardly faster than the transerrer arm the bobbin tip T may tend to rise relatively to the center of the bobbin. Such motion, however, is effectively prevented by the foot 40.

If the bobbin should be only partly wound with weft so that the foot 22 does not engage any part of the bobbin or its weft the compressible foot 40 will be in position to limit upward movement of the tip end T of the bobbin during the transferring operation. Also, if the transerrer arm is designed primarily for a short bobbin but is desired to be used with a longer bobbin, the carrier or plate 30 can be added to foot 22 to control a long bobbin in its descent during transfer.

The bottoms of the several feet which engage the bobbin are preferably at different levels. The foot 20 is the lowest of the three feet and will ordinarily be the first to engage the bobbin during transfer. The second foot 22 is somewhat higher than the foot 20, while the bottom of foot 40 will be at an elevation intermediate the bottoms of feet 20 and 22. During transfer when the relations are as set forth in Fig. 2 there is likely to be some compression of the foot 40 but the latter because of its resilience recovers its normal shape after transfer.

From the foregoing it will be seen that I have provided an improved form of bobbin transfer having three bobbin engaging feet one of which is for the intermediate part of the bobbin, and the third of which is adjacent to the bobbin tip to prevent upward movement of the latter during transfer. It will also be seen that the auxiliary or third foot 40 is mounted on a carrier 30 which can be applied to or removed from the main body of the transerrer arm as desired, depending upon the length of the bobbin. The auxiliary foot 40 is made of compressible material and extends downwardly preferably to a position lower than foot 22, but preferably not as low as foot 20. Vertical adjustment of carrier 30 permits use of foot 40 with various diameters of weft on the bobbin.

Having thus described my invention it will be seen that changes and modifications may be made therein by those skilled in the art without departing from the spirit and scope of the invention and I do not wish to be limited to the details herein disclosed, but what I claim is:

1. In a transerrer arm for a reserve bobbin

having a butt and tip, a foot on the arm to engage the butt end of the bobbin, a second foot on the arm for engagement of the bobbin intermediate the butt and tip thereof, and a third foot for engagement of the bobbin adjacent to the tip thereof secured to the second foot in adjusted vertical position relatively to the first and second feet to engage bobbins of different weft diameters.

2. In a transerrer arm for a reserve bobbin having a butt and tip, a foot on the arm to engage the butt end of the bobbin, a second foot on the arm for engagement of the bobbin intermediate the butt and tip thereof, a third foot for engagement of the bobbin adjacent to the tip thereof, and slot and screw means to secure the third foot to the second foot in adjusted vertical position relatively to the transerrer arm to engage bobbins of different weft diameters.

3. In a transerrer arm for a reserve bobbin having a butt and tip, a foot on the arm to engage the butt end of the bobbin, a second foot on the arm for engagement of the bobbin intermediate the butt and tip thereof, a carrier for the second foot extending from the latter toward the bobbin tip, a body of deformable resilient material for engagement with the bobbin adjacent to the tip thereof clamped to said carrier, and means securing said carrier to the second foot in vertically adjusted position relatively to the second foot to enable said body of material to engage weft bobbins of different diameters.

4. In a carrier for a transerrer arm, said carrier comprising a flat body formed with two flanges one of which is adapted for attachment to the transerrer arm, and a foot secured to the other flange for engagement with the bobbin adjacent to the tip thereof.

5. In a carrier for a transerrer arm, said carrier comprising a body formed with laterally spaced vertical flanges one of which is adapted for attachment to the transerrer arm, and a bobbin engaging foot secured to the other flange.

6. In a carrier for a transerrer arm, said carrier comprising a flat body having laterally spaced vertical flanges formed thereon one of which is adapted for attachment to the transerrer arm, a foot for the other flange to engage the bobbin adjacent to the tip thereof, and means including a vertical plate securing the foot to said other flange.
